UNITED STATES PATENT OFFICE

156,400

CHAPS FOR GARDENING OR LIKE PURPOSES

Sylvanus F. Beatty, Three Rivers, Mich.

Application April 1, 1948, Serial No. 145,475

Term of patent 3½ years

(Cl. D3—17)

To all whom it may concern:

Be it known that I, Sylvanus F. Beatty, a citizen of the United States, residing at Three Rivers, in the county of Saint Joseph and State of Michigan, have invented a new, original, and ornamental Design for Chaps for Gardening or Like Purposes, of which the following is a specification, reference being had to the accompanying drawing, forming part thereof, wherein:

Fig. 1 is a front elevational view of a pair of chaps for gardening or like purposes, showing my new design, and

Fig. 2 is a rear perspective view thereof.

I claim:

The ornamental design for chaps for gardening or like purposes, substantially as shown.

SYLVANUS F. BEATTY.
